ing so that the restrained end of the spring made a small angle (ψ) with the horizontal. The convention adopted is $+\psi$ = an initially upward inclination of the spring, $-\psi$ = an initially downward inclination of the spring.

Figure 6 is a plot, at different positive values of ψ , of the angular disposition of the free end of the spring (α)/applied load in grams.

Assuming, for example a value of $\psi=+30^\circ$, on increasing the load g the curve A'-B is traversed. At B the spring extends suddenly, the free end lengthening and twisting considerably for a very small increase in load until the position represented by C is reached. Further loading produced a more gradual extension and twist, following the curve C-C'.

On reducing the loading, the spring does not contract violently at C but continues to follow an extension of the curve C'-C to the point D when a sudden contraction and twist for a small decrease in loading brings the spring to the conditions represented by A. Further reduction in loading follows the course A-A'.

For the spring employed it was found that on reducing the angle ψ similar curves were obtained on plotting α/g until a value between $\psi=+7.5^\circ$ and $\psi=+5^\circ$ was reached when the abnormal behaviour of the spring disappeared and simple inflection curves were obtained.

The critical angle (ψ_{cr}) is defined as the value or values of ψ (+ive or -ive) at which the points A and B coincide.

The critical loading (g_{cr}) is defined as the value of g at the point A at the critical angle.

If the spring has a number of turns the conditions illustrated on Figure 6 may recur at higher values of g .

Thus a spring may have a plurality of values of ψ_{cr} both positive and negative.

The spring is defined as being in a state of extreme sensitivity when it is mounted at an angle approximately to ψ_{cr} under a critical loading (g_{cr}) corresponding to ψ_{cr} .

The spring described with reference to Figure 1 has been found to possess two primary states of extreme sensitivity.

- (1) at $\psi_{cr}=+6^\circ$ under load of approximately 51 grams.
- (2) at $\psi_{cr}=-19^\circ$ under load of approximately 77 grams.

Secondary and tertiary states of extreme sensitivity are probable at higher values of g .

Figure 6 as described above illustrates the behaviour of the spring with reference to angle of twist (α). It is to be noted, however, that the relationship between α and h for different values of ψ is very nearly linear above and below the zones of instability between the position A and B, C and D.

Figure 7 is a plot of α/h at different values of ψ . Measurement or indication of small changes in the value of g when operating in the state of extreme sensitivity may thus be made with respect to changes in length or in angle of twist.

Figures 8 to 9 show plots of the variables hereinbefore described as determined for another spring of the type illustrated in Figure 1 and Figure 2 and having the following dimensions:

Length along the spiral	cms.	81
Width	mm.	7.75
Thickness	mm.	0.38
Thus area of cross-section	sq. mm.	2.95
Ratio of width/thickness		20.4

Free of distorting forces the spring had $3\frac{1}{4}$ windings. The outer end was approximately 27 mm. from the centre of the geometric form.

The spring was clamped at its inner end and mounted to permit inclination of the end of the spring while maintaining the longer side of the spring in a vertical plane.

Figure 8 is a plot of α /applied load at different values of ψ .

A region of high sensitivity is noted at a value of $\psi=+17^\circ$ and a loading of approximately 238 grams.

Figure 9 is a plot of ψ/α for six different values of the load, approximating to the critical loading, between 236 and 239 grams.

It is noted that at a value of approximately 238 grams, the distortion is substantially independent of the angle of application of the loading between values of 13° and 17° . Similar curves are obtained when tilting the clamped end in a direction which is at right angles to ψ (i. e. ϕ).

In general it is preferred that an instrument according to the present invention be operated under a load such that the distortion is nearly independent as possible of the angle of loading (ψ and ϕ) for small variations of ψ and ϕ . Under these conditions the effect of errors or variations in the levelling of the instrument are minimised.

One form of construction of a gravimeter according to the present invention will be described in detail as illustrated in Figures 10 to 15 of the accompanying drawings.

A rigid rectilinear framework 1 has an adjustable spring mounting clamp 2 attached to the lower side of its upper surface, and to the movable part of the mounting clamp 5 is rigidly clamped the inner end of the coiled flat section spring 3. The spring, free of distorting forces, comprises approximately three complete turns. To the outer end of the spring, which under the influence of the masses attached thereto depends below the upper fixed end, there is attached a small mirror 4 and to the mirror one end of a light vertical rod 5. The lower end of the rod is attached to the upper end of a vertical, delicate, helical spring 6, the lower end of the helical spring being attached to a vertical rack 7, carried by 25 a slide rigidly secured to the framework 1 and engaging a pinion 9 operated by a horizontal shaft 10 projecting through one side of the framework 1. Within the spring 3 there is extended a vertical delicate, helical spring 8 attached at its upper end to the mounting clamp 30 2 and at its lower end to the mirror 4. The vertical rod 5 carries a horizontal double-bladed vane 11 which moves between quadrants 12 disposed as in a quadrant electrometer, that is, comprising two diagonally opposed quadrants in a plane above the vane and two diagonally 35 opposed quadrants situated below the vane, preferably two adjacent quadrants, that is one quadrant above the vane and one below. The vane is attached to a movable support 13 and may be adjusted in a vertical direction between their corresponding rigidly held quadrants. A horizontal damping disc 14 is mounted on the vertical rod 5 near its lower end, having its periphery between the pairs of poles 15 of two diametrically positioned horse-shoe magnets rigidly attached to the framework or box. Preferably the vane, quadrants and disc are 40 constructed of a light metal, such as aluminum. Preferably clamps are provided to lock the vertical rod against horizontal movement and the disc against vertical movement when the apparatus is not in use.

Pairs of quadrants are connected to an electronic circuit 50 by which readings are made of the force of gravity after calibration of the instrument. A variable capacity condenser of this type is very sensitive and permits accurate measurement of the force of gravity.

Alternatively a photo-electric method can be employed 55 using a beam of light reflected by the small mirror attached at the head of the vertical rod.

Alternatively a radio active method using a source of 60 radio active material which changes the ionisation within two or more ionisation chambers, the chambers and the source being capable of relative movement.

By adjustment of the vertical movable quadrants a position can be reached in which the instrument is self-compensating for small angles of tilt.

The adjustable mounting for the sensitive spring may 65 be constructed in numerous ways, and the form of construction employed is not an essential feature of the invention.

Figures 11 and 12 illustrate one form of spring mounting for use in a gravimeter according to the invention.

Figure 11 is an elevated view and Figure 12 a plan of the apparatus.

The sensitive spring 20 is clamped on to support 21 carried by bevel gear 22 mounted on a cranked arm 23 supported by the casing 19. A second bevel gear 24 engages gear 22 and is carried on a shaft 25 within one arm of 75 23, adjusting wheels 26 and 27 are carried by the arm 23 and shaft 25 to enable the spring 20 to be tilted in two directions mutually at right angles.

Figures 13 and 14 illustrate a second form of spring 80 mounting. Figure 14 is an elevated view and Figure 13 is a plan.

The spring 30 is clamped on to support 31 attached to a ball socket 32 carrying four vanes, 33-36. The socket 32 encloses a spherical ball 37 rigidly supported by a rod 85 38 from the casing 39. Two adjacent vanes 33 and 34 are

supported from the casing 39 by spring loaded rods 40 and 41. The other two vanes 35 and 36 are adjustably positioned by adjusting screws 42 and 43 which are threaded through the casing 39.

In general it is preferred that an instrument according to the present invention be operated under a load such that the distortion is virtually independent of the angle of loading (ψ) for small variations of ψ . Under these conditions the effect of errors or variations in the levelling of the instrument are minimised.

The following general laws enable the determination of the value of unknown factors when certain characteristics of the spring are known.

Law 1.—For constructing a sensitive spring for a given weight the following approximative formula ($\pm 10\%$) may be used.

$$W = 0.4 \times \frac{E \cdot h \cdot b^3}{d^2}$$

where

E =modulus of elasticity

h =width of the spring

b =thickness of the spring

d =length of the sensitive part of the spring

Taking a spiral spring of $1\frac{1}{2}$ turns in the initial shape and using $+$ inclinations, d can be taken as approximately equal to half of the circumference of the first turning (at the clamped end) of the spiral. When using negative inclinations W^- is approximately equal to $1.5W^+$. For $-\psi$ inclination $W^- = 1.25 W^+$. The shape factor σ is supposed to have the value of between 0.03 and 0.9. This factor is defined by

$$\sigma = \frac{R_i - R_o}{n \times R_a}$$

where R_i =radius at the inner, clamped end, R_o =radius at the outer end, n =number of windings.

The values obtained are also valid for springs with $3\frac{1}{2}$ windings, but the absolute value of the angles $+$ or $-$ will be different.

The following examples illustrate the calculation of the value of W when other characteristics of the spring are known.

EXAMPLE 1

$h=0.192$ in.; $b=0.005$ inch. $E=1.4 \times 10^{10}$ gr./in.²;

$R_i=1.5$; $n=0.4$

W calc.: 6 gr. W obs.: 6.6 gr. for $+\psi$ incl. ϕ

W calc.: 9 gr. W obs.: 10.6 gr. for $-\psi$ incl. ϕ

W calc.: 7.0 gr. W obs.: 7.1 gr. for $-\psi$ incl.

EXAMPLE 2

Using a spring having the same characteristics as in Example 1 except that the value of $b=0.008$ in. the following theoretical and practical results were obtained:

W calc.: 25 gr. W obs.: 23.0 gr. for $+\psi$ incl. ϕ

W calc.: 37 gr. W obs.: 35.5 gr. for $-\psi$ incl. ϕ

W calc.: 28.5 gr. W obs.: 27.5 gr. for $-\psi$ incl.

Law 2.—As the diameter of the spiral increases with s_0 (the overall length) if the shape remains similar ($\psi=\text{const.}$) W is also proportional to $1/s_0^2$ in this case.

Law 3.—Another dimension which one wishes to be able to calculate beforehand is the vertical length l_{cr} of the spring in its sensitive state compared with the overall length s_0 . The ratio

$$\frac{l_{cr}}{s_0}$$

is independent of b , h and W , so that all springs of the same length and shape show the same ratio of l_{cr} for the same angle of inclination.

The ratio of

$$\frac{l_{cr}}{s_0} = I (= \text{relative working length})$$

is given in the following table:

I values

$+\psi$	$-\psi$	$-\phi$	Turns
0.41	0.64	0.53	$1\frac{1}{2}$
0.25	0.41	0.33	$3\frac{1}{2}$

The ratio of $I^{1/2}$ to $I^{3/2}$ is for every shape 1.6.

It is apparent that $+\psi$ inclination gives the shortest and $-\psi$ inclination the longest relative working length.

Law 4.—The ratio between lengthening and twisting of the spring. (K mm./degree) is a linear function of s_0 and therefore also of l_{cr} . According to the figures given in the section above K is lowest for $+\psi$ and increase for $-\phi$ and then for $-\psi$.

For $1\frac{1}{2}$ turns and $s_0=150$ mm. K is in the order of magnitude of 0.3 mm./degree for $-\phi$ and increases to 0.6 for s_0 of about 400 mm.

For the same value of l_{cr} the value of K is substantially lower for $3\frac{1}{2}$ turns than for $1\frac{1}{2}$ turns.

The invention is further illustrated but in no way limited with reference to the following examples.

EXAMPLE 3

A steel clock of width (h) 0.755 inch, breadth (b) 0.008 inch, h/b ratio of 94 and comprising $1\frac{1}{2}$ turns was investigated to determine its states of extreme sensitivity. These were found to occur under the conditions shown in the following table.

25	Angle of inclination, degrees	W. (grams)	l_{cr} (cms.)
$+\psi$	8	75.3	15.3
$-\psi$	27	120.1	23.1
$-\phi$	8	85.6	19.0

EXAMPLE 4

A steel clock spring of width (h) 0.755 inch, breadth (b) 0.008 inch, h/b ratio of 94 and comprising $3\frac{1}{2}$ turns was investigated to determine its states of extreme sensitivity. These were found to occur under the conditions shown in the following table.

45	Angle of inclination, degrees	W. (grams)	l_{cr} (cms.)
$+\psi$	14	61.8	16.9
$-\psi$	20	99.4	28.0
$-\phi$	4	124.3	38.2
$-\psi$	15	81.1	22.5

It is frequently advantageous that the action of the sensitive spring should be modified by the use of a subsidiary helical spring of conventional type connected in parallel. The subsidiary spring should be very weak in comparison with the sensitive spring and its action is to restrict the movement of the sensitive spring outside the operating range of movement and to stabilise the action of the sensitive spring.

In order to attain conditions under which the effect of variations of the angle of levelling are minimised, it is advisable to suspend the working part of the gravimeter within a fluid in a sealed vessel, so that the working part maintains, automatically, its vertical position.

I claim:

1. A sensitive gravimeter comprising a coiled spring and a comparatively weak helical spring, said coiled spring being of diminishing radius of curvature towards one end thereof of material having a cross-section of width/thickness ratio in the range 10:1 to 100:1 and constituting not substantially less than 1.25 turns in the unextended state, means attached to one end of the coiled spring capable of movement under the action of the force of gravity, and a mounting for the other end of the coiled spring to support said spring so that the longitudinal axis, in the unextended state subtends an angle in the range of from 5° to 85° to the vertical, the angle being such that under the influence of the force of gravity 70 the coiled spring is extended into a state of extreme sensitivity, the action of the coiled spring being modified by said comparatively weak helical spring, rigidly connected to the coiled spring at each end thereof.

2. A sensitive gravimeter as specified in claim 1 in which in the operating position the angle of inclination of the axis of the coiled spring to the vertical is in the range 10-40°.

3. A sensitive gravimeter comprising a coiled spring of diminishing radius of curvature towards one end thereof of material having a cross-section of width/thickness

ratio in the range 10:1 to 100:1 and constituting not substantially less than 1.25 turns in the unextended state, means attached to one end of the spring capable of movement under the action of the force of gravity, and a mounting for the other end of the spring to support the spring so that the longitudinal axis, in the unextended state subtends an angle in the range of from 5° to 85° to the vertical, the angle being such that under the influence of the force the spring is extended into a state of extreme sensitivity, in which the end of the spring capable of movement under gravity is connected to a quadrant electrometer.

4. A sensitive gravimeter as specified in claim 3 in which in the operating position the angle of inclination of the axis of the spring to the vertical is in the range 10-40°.

5. A sensitive gravimeter as specified in claim 3 in which the end of the spring capable of movement under gravity is connected to a movement damping device.

6. A sensitive gravimeter comprising a coiled spring of diminishing radius of curvature towards end thereof of material having a cross-section of width/thickness ratio, in the range of 10:1 to 100:1 and constituting not substantially less than 1.25 turns in the unextended state, means attached to one end of the spring capable of movement under the action of the force of gravity, and a mounting for the other end of the spring to support the spring so that the longitudinal axis, in the unextended state subtends an angle in the range of from 5° to 85° to the vertical, the angle being such that under the influence of the force the spring is extended into a state of extreme sensitivity, and in which the end of the coiled spring capable of movement under gravity is connected to one end of a vertical helical spring, the other end of said

helical spring being attached to a vertically adjustable mounting.

7. A sensitive gravimeter as specified in claim 6 in which in the operating position the angle of inclination of the axis of the spring to the vertical is in the range 10-40°.

8. A sensitive gravimeter comprising a coiled spring of diminishing radius of curvature towards one end thereof of material having a cross-section of width/thickness ratio in the range 10:1 to 100:1 and constituting not substantially less than 1.25 turns in the unextended state, means attached to one end of the spring capable of movement under the action of the force of gravity, and a mounting for the other end of the spring to support the spring so that the longitudinal axis, in the unextended state subtends an angle in the range of from 5° to 85° to the vertical, the angle being such that under the influence of the force the spring is extended into a state of extreme sensitivity, in which the action of the coiled spring is modified by a comparatively weak helical spring rigidly connected to the sensitive spring at each end thereof and in which the end of the sensitive spring capable of movement under gravity is connected to one end of a vertical helical spring, the other end of said vertical helical spring being attached to a vertically adjustable mounting.
